UNITED STATES PATENT OFFICE

WILLIAM A. GRAHAM, OF CHICAGO, ILLINOIS, AND WILLIAM F. DOYLE, OF WASHINGTON, DISTRICT OF COLUMBIA

COMBINED CHAIR, TABLE, AND BED

Application filed February 25, 1926. Serial No. 90,585.

(GRANTED UNDER THE ACT OF MARCH 3, 1883, AS AMENDED APRIL 30, 1928; 370 O. G. 757)

This invention relates to improvements in furniture and more particularly to a combined chair, table and bed, or a one-half bed, it requiring two chairs to provide one bed.

5 The invention described herein, if patented, may be manufactured and used by or for the Government for governmental purposes without payment of any royalty thereon.

An object to this invention is to provide a 10 piece of furniture especially adapted for Army use wherein are combined simplicity, durability and economy.

A further object being to provide a convertible unit that may be so folded as to leave 15 no projecting portions that may be damaged in transportation, the entire unit folding into compact rectangular form, appearing similar to, and may be handled, stacked and shipped as easily and safely as an ordinary packing 20 box.

A further object being to provide a construction of simple character, which not only represents economy both in manufacture and replacement or repairs, but avoids damage 25 due to lack of knowledge of operation and diminishes complication which always leads to failure in operation, in articles of this character.

A further object being to provide an article of such a construction as to withstand the rough usage encountered in transfers of same over long distances by methods that would in a short time irreparably damage the ordinary construction of furniture.

30 A further object being economy not only of construction, repair, space in transportation and other features above indicated, but as to the economy that exists owing to the plural use of an article of this character, in that one or more persons may occupy a single room, which will serve as a living room, an office room or a bed room as desired, the furniture useful for instance in a bed room, not occupying useful space while room is being used 35 for other purposes, but would be convertible when required into useful bed room furniture. In other words a single room with furniture of this character is as useful as two or even three rooms, for instance a living room or study, a dining room or a bed room.

A further economy possible in this invention is found in the problem of crating and shipping furniture from time to time by officers in the Army as they are shifted from place to place. The crates necessary for the 55 protection of chairs, tables and beds of the ordinary construction, represent so much value that it is very wasteful to destroy them after each move, but if an attempt is made to preserve them, any one familiar with the 60 latter efforts, knows that at a large army post, it requires an entire building of considerable proportions to house the crates, with the danger of fire and the difficulty of locating a particular crate for the piece of 65 furniture for which it is intended. The improved piece of furniture covered by this application requires no crating, it being necessary simply to wrap the folded unit securely in burlap, in which condition it may be 70 shipped, stacked and handled with safety and economy where damage, space and weight are considered.

Similar numerals indicate corresponding parts in all the figures of the drawings in 75 which:

Fig. 1, is a side view of the improved combination furniture unit arranged as a bed.

Fig. 2, is a plan view of Fig. 1.

Fig. 3, is a vertical longitudinal section of 80 Fig. 1.

Fig. 4, is a horizontal section of Fig. 1 beneath the cushions.

Fig. 5, is a side view of the improved furniture unit, arranged as a chair.

Fig. 6, is a rear view of Fig. 5.

Fig. 7, is a side view, arranged as table.

Fig. 8, is a rear view of Fig. 7.

Fig. 9, is a detail section of the lower end of one of the legs without the extension.

Fig. 10, is a perspective view of the lower end of one of the legs showing the extension and supporting brace.

Fig. 11, is a similar view of the extension alone.

Fig. 12, is an edge view of one of the chair arms showing its rear mounting.

Fig. 13, is a perspective view of one of the combination units packed ready for shipment.

Fig. 14, is a detail showing the upper end of the brace for the leg and the latch for locking same.

Fig. 15, is an enlarged detail of the locking mechanism at the ends of the drawer.

Fig. 16, is an enlarged detail of the manner of locking a leg in its folded position.

Fig. 17, is a detail view of the leg brace and the pin and slot lock therefor.

Reference now being had to the drawings by numerals, 1 indicates the seat portion, 2 the back, 3 the legs, and 4 the arms of the improved furniture unit.

Reversible and interchangeable cushions are provided for the seat and back of the chair (see Fig. 5).

The seat member 1 consists of the frame having side members 7 preferably of wood of the proper thickness, and lower or base member 8 and front and rear cross members 9 and 10. A drawer 11 having sides 11a, the bottom 12, and front and rear members 13 and 14, respectively, is arranged to slide between members 8 and the end members 9 and 10 and be provided with disappearing hand pulls members 15 and 16 in the front and rear end members of the drawer, to provide for the withdrawal of the drawer in either direction. Said hand pulls are preferably provided with a latch member 17 which engages keepers 18 in the cross members 9 and 10, said latch being withdrawn from engagement with the cross member by swinging the hand pull out into its horizontal position, which permits sliding the drawer toward the operator as hand pull is grasped and raised into position to pull the drawer, the latch on the end of drawer opposite to that where hand pulls are lifted, passes through groove 19 in the cross piece. By this means, the drawer may for convenience, be opened from in front or from in rear of the chair and yet be locked against accidental movement in either direction.

Immediately above cross members 9 and 10 is arranged the seat consisting of front and rear portions 20 and 21 divided into staggered slats 22 having cut-away portions 23 therebetween in which complementary portions of the other member slide, to permit an elongation of the seat (see Fig. 4) for purposes that will be explained later.

The outer slats 24 of the extension seat member 20 are wider than the intermediate slats and are provided with swinging supports 25 of approximately the same thickness as the member 24, pivoted at 26 and adapted to swing and to fold into an opening 27 flush with the faces of the slat 24. A stop 28 is provided to limit the upward movement of the swinging end of the support 25. A brace 29, pivoted on support 25 at 30 having a slot 31 provided with a lock notch 32 at its upper end operating over a pin 33 to limit the outward and inward swing of the support 25.

The inner end of slat members 24 are provided with lugs 34 adapted to engage stop lugs 35 to limit the outward movement of the extension member 20 of the seat. The seat of the chair as described serves the dual purpose both as a seat when the unit is in use as a chair in its retracted or folded position and as a support for one-half of the length of the bed or couch when in its extended position.

The back 2 serves three purposes, one as a chair back, another as a table top and third as a head or foot board of the bed and consists of side members 36 provided with end portions 37 between which is a cut-away portion 38 into which the arm fits when in its folded position. The side members are connected with a solid board surface 39, so finished on its outer face as to provide a table top when in its horizontal position.

Rising from the inner face of the side members 7 of the seat, are preferably sheet metal brackets 40 on which the back 2 of the chair, is pivoted at 41. Across the lower end of the back 2 is hinged at 42, flap board 43 adapted to swing down and close the space between the back board 39 and the rear cross member 44 of the seat, when the back is folded down on the seat to form a table or for packing.

Across the top of the back is an elongated compartment 80 into which access may be had through closure 81 hinged at 82. Said compartment is designed to receive a pillow, extra pillow cases or the like, or table coverings, either fancy for living room or white table cloths.

The legs 3 are of a folding and extension type and consist of the upper or main portion 45, hinged at 46 to swing inwardly, said main portion of the leg being provided with a brace 47, pivoted at 48 at the lower end of leg member 45 and extending up between keeper plates 49, said plates being arranged parallel across the bottom of the seat of the chair and are provided with slots 50 in which pins 51 extending out from the upper end of brace 47, operate as the leg 45 is swung into its folded position in line with keeper plates 49. When the legs are extended and brace pins 51 are in their outer position, a lock latch 52 pivoted at 53 and provided with an angular extension 54, is adapted to automatically snap into position behind pin 51 and lock the leg in its extended position. A spring 55 tends to drop the latch into engagement with the pin and the latch must be tripped to permit the leg to be folded.

When using this combination furniture unit as a chair or bed the legs are required to be the same length, but when used as a table approximately 6 inches more height is required which is added by extension 56 added to the lower end of the leg.

The leg extension 56 (see Figs. 10 and 11) is pivotally mounted at 57 on arms 58 pro-

jecting from the upper end of the leg member and as seen are mounted on opposite sides of the pivot of brace 47 and when leg portion 45 and its extension are brought into alignment, upper and lower bolt retaining members 59 and 60 mounted on the leg 45 and extension 56, respectively, are also brought into alignment and bolts 61 lock the parts of the legs in said position. By reference to Fig. 9 a friction spring 62 is seen buried in the leg 45 in rear of bolt 61 against which the outer end of the spring presses to provide friction to retain the bolt in its adjusted position.

When the leg is folded for shipment or storing the extension is adjusted at the end of the leg portion 45 or as it is required when the device is arranged as a table and is in that position folded on hinge 46 across approximately one-half of the width of the chair, snugly up against the base 8 of the seat. In said position the bolt 61 is moved into position to engage the retaining members 59 and 60 and maintain the leg and its extension in alignment, and it is when said bolt is slid into engagement with the retaining member 60 on the leg extension 56 that a lug 63 on the bolt, engages a pin 64 on the chair frame and holds the leg in its folded position.

When the lower or extension member 56 of the leg is not in use and the unit is in the form of a chair or bed, it is swung into engagement with the brace 47 (see Fig. 6) where it is secured in any preferred manner.

Arm 34 of the chair (see Figs. 1, 2, 5 and 7) are so formed as to fill the cut-away portion 38 in the side members of the back. The arm is mounted at its rear end on a bracket 65 secured on the inner face of member 36 by a swivel joint 66 or one permitting universal movement of the arm, whereby same may be swung from the position as seen in Fig. 5 for use as an arm for the chair or into its folded position in the cut-away portion 38 of the back, with its outer face flush with the outer face of side member 36 of the back and side member 7 of the seat (see Fig. 7). The front end of arm 4 may be provided with a flat metal support 67 having a swivel connection 68 with the arm and provided with a slot

69, enlarged at 70, the latter to pass over a headed pin 71 mounted in the seat frame (see Figs. 4 and 5). By said means the outer end of the arm 4 is firmly held in position when the unit is used as a chair or if the arm 4 is lifted to bring the enlarged portion 70 of slot 69 into position to be removed from pin 71, the support 67 may be folded up against the inner face of arm 4 and said arm be turned and adjusted into cut-away portion 38 as described, where it may be retained in any preferred manner.

By reference to Figs. 1, 4, 5 and 7 will be seen aligning and retaining plates 72, mounted on the outer face of the seat frame and ar-

ranged to project slightly above the upper edge of members 7. And when the back 2 of the chair is folded down on the seat frame as a table or for packing, the widened ends of the side members 7 rest within said plates 72 and are held firmly against lateral movement.

The cushions are preferably of a box frame construction consisting of a metal frame 73 in which springs 74 are mounted and are covered by padding 75 of any preferred character, the construction being similar to that of a removable auto seat. The cushions are made in pairs 76—77, corresponding in every way as to thickness, length and width. Cushion 76 is adapted to form the major part of the back cushion and rests when the unit is used as a chair, as a table or when packed, between the side members 36 of the back 2. The roll 78 at the top of the back is preferably padded and tufted and covered by the same material as the cushions.

The other cushion 77 is adapted to form the seat of the chair and the two cushions 76 and 77 being identical, will permit interchangeable and reversible adjustment as to their positions at the back or seat of the chair. If preferred, the cushion 76 may be secured at 79 to cushion 77, which will permit the adjustment of one cushion by the other.

The drawer 11 in the seat and compartment 80 in the back are provided for the reception, primarily, of bedclothing, but may be used for other purposes if desired, the drawer is designed to receive one or two blankets and two sheets folded flat.

With a pillow and one or two extra pillow cases in the chair back, and two sheets and two blankets in the drawer, the two chairs which are necessary for one bed, will contain ample covering and changes required to provide a comfortable and hygienic bed.

In operation, by reference to Figs. 5 and 6, the unit is arranged as a chair which approximates very closely a Morris chair as to appearance and comfort, and in fact possesses greater comfort, due to the fact that the seat and back cushions are of a full box spring construction, while the Morris chairs are provided with simply a springless pad packed with cotton or hair.

In Figs. 7 and 8 the unit is shown as a table with the back of the chair folded down and the solid back of the chair forming the table top. As a table the arms 4 are folded into space between and lie flush with the enlarged end portions of the side members of the chair back and the legs are lengthened by swinging their extensions into position.

In Figs. 1, 2, 3 and 4 the unit is arranged as a couch with two chairs facing each other and having their extensions brought together and the seat cushions advanced, with the back cushions slid down in rear of the seat cushions to complete a couch of box spring construction, having head and foot boards.

Should a double bed be desired, two couches pushed up against each other, with their inner arms folded up into position they occupy when the units are adjusted as tables will provide a very comfortable double bed.

5 A table of the regulation height, and about 3 feet square may be provided by each unit, or a table of greater dimensions by putting two or more tables, either in line or parallel, for instance if four units are used a table 6 feet square may be provided.

Fig. 13 illustrates a single unit packed ready for shipment.

15 One unit when folded will occupy about 13½ cubic feet of space and is of rectangular form, capable of packing without loss of space, measuring 3 feet square and 18 inches deep.

20 Four units when packed will occupy 54 cubic feet, or a space 6 feet high and 3 feet square. Said four units will provide the following nineteen combinations:

25 Four chairs; three chairs and one 3 x 3 table; two chairs and two 3 x 3 tables; two chairs and one bed; one chair, one table and one bed; two tables and one bed; two beds; two chairs and one 3 x 6 table; one chair and one 3 x 9 table; one table 3 x 12; one table 6 x 6; one chair, one 3 x 3 table and one 3 x 6 table; one 9 x 3 table and one 3 x 6 table; one 6 x 3 table and two 3 x 3 tables; four 3 x 3 tables; two 6 x 3 tables; one 6 x 3 table and one bed; twin beds; one double bed.

30 The improved combination furniture unit above described is especially adapted for use by Army officers or others desiring to economize as to cost of transportation, space, breakage and cost of packing and the utilization of the minimum rooms or floor space, or in combining facilities for office equipment, living, eating and sleeping accommodations in one room, wherein the furniture may all be used in all the instances cited, and thereby leave no idle furniture to occupy useful space under any of the several conditions referred to.

Having described our invention, what we claim is:

35 1. A combined chair, table and bed unit adapted to be compactly folded for shipment comprising, a seat frame having a seat portion and an extension, legs foldably mounted on said frame and adapted to support the parts when arranged as a chair, leg extensions foldably mounted on said legs adapted to support the parts when arranged as a table, a combined chair back and table top having cut-away side members, pivotally mounted on said seat portion, adapted to rest on said seat portion when the parts are arranged as a table and folded for shipment, chair arms foldably mounted on said combined chair back and table top, and on said chair frame, adapted to fill the cut-away portions in said chair back and table top, when

the parts are arranged as a table and folded for shipment, and removable back and seat cushions adapted to rest on the seat portion and on said extension when the parts are arranged as a bed unit.

2. A combined chair, table and bed unit adapted to be compactly folded into rectangular form for shipment comprising, a seat frame having a seat portion and an extension, legs foldably mounted on said frame adapted to support the parts when arranged as a chair, and swing up against said seat frame when arranged for shipment, leg extensions foldably mounted on said legs adapted to support the part when arranged as a table, a combined chair back and table top pivotally mounted on said seat portion adapted to rest on said seat portion when the parts are arranged as a table and folded for shipment, a compartment at the upper end of said combined chair back and table top for the reception of bed or table coverings, chair arms foldably mounted on said chair back and removable back and seat cushions adapted to rest on the seat portion and on said extension when the parts are arranged as a bed unit.

3. A combined chair, table and bed unit adapted to be compactly folded into rectangular form for shipment comprising, a seat frame having a seat portion and an extension, a compartment arranged in said seat frame adapted to receive bed or table coverings, legs foldably mounted on said frame adapted to support the parts when arranged as a chair and swing up against said seat frame when arranged for shipment, leg extensions foldably mounted on said legs adapted to support the parts when arranged as a table, a combined chair back and table top pivotally mounted on said seat portion adapted to rest on said seat portion when the parts are arranged as a table and folded for shipment, a compartment arranged at the upper end of said combined chair back and table top for the reception of bed or table coverings, chair arms foldably mounted on said chair back and removable back and seat cushions adapted to rest on the seat portion and on said extensions when the parts are arranged as a bed unit.

4. A combined chair, table and bed unit adapted to be compactly folded into rectangular form for shipment comprising, a seat frame having a seat portion and an extension, legs foldably mounted on said frame adapted to support the parts when arranged as a chair and fold up against the chair frame when arranged for shipment, leg braces pivoted to the legs at their lower ends and slidably mounted at their upper ends in slotted keepers arranged on the chair frame, adapted to limit the outward swing of said legs, leg extensions adapted to support the parts when arranged as a table and

frame having a seat portion and an extension, legs foldably mounted on said frame adapted to support the parts when arranged as a chair and fold up against the chair frame when arranged for shipment, leg braces pivoted to the legs at their lower ends and slidably mounted at their upper ends in slotted keepers arranged on the chair frame, adapted to limit the outward swing of said legs, leg extensions adapted to support the parts when arranged as a table and swing into contact with said braces when the parts are arranged as a chair, dual means for locking the leg extensions in their extended positions and locking the legs in their folded positions comprising bolts mounted on the lower ends of the legs entering keepers on the extensions, said bolts having projecting lugs adapted to contact with studs on the chair frame to maintain the legs in folded position, a combined chair back and table top pivotally mounted on said seat portion adapted to rest on said seat portion when the parts are arranged as a table and folded for shipment, chair arms foldably mounted on said chair back and removable and interchangeable back and seat cushions adapted to rest on the seat portion and on said extension when the parts are arranged as a bed unit.
